J. L. H. HAND.
INSTRUMENT FOR TAKING SOUNDINGS.
APPLICATION FILED DEC. 11, 1916.

Patented Oct. 22, 1918.

Inventor.

John L. H. Hand.

By William J. Gaestel
Attorney.

UNITED STATES PATENT OFFICE.

JOHN L. H. HAND, OF PHILADELPHIA, PENNSYLVANIA, ASSIGNOR TO JOHN E. HAND & SONS CO., OF PHILADELPHIA, PENNSYLVANIA, A CORPORATION OF NEW JERSEY.

INSTRUMENT FOR TAKING SOUNDINGS.

1,282,075.

Specification of Letters Patent.

Patented Oct. 22, 1918.

Application filed December 11, 1916. Serial No. 136,219.

To all whom it may concern:

Be it known that I, JOHN L. H. HAND, a citizen of the United States, residing at Philadelphia, in the county of Philadelphia and State of Pennsylvania, have invented a certain new and useful Improved Instrument for Taking Soundings, of which the following is a specification.

The principal object of the present invention is to provide an instrument for taking soundings in which is combined maximum simplicity, durability and efficiency in order to render the same commercially more valuable than like instruments now upon the market.

Another object of the present invention is to provide an instrument of this character in which the column of water brought up with the instrument, when taking soundings, designates the depth of the body of water sounded more accurately than with instruments of like character in present use.

A further object of the present invention is to provide an instrument for taking soundings in which is employed a valve of non-returnable characteristics for the positive prevention of escape of air from the instrument and of such construction as to reduce to a minimum the possibility of the same getting out of order.

A further object of the present invention is to provide a readily detachable valve of this character in order that substitutions thereof may be quickly effected if desired.

A still further object of the present invention is to provide a valve of this character which serves the additional function of an efficient gasket between the instrument body and cap.

With these and other objects in view, the invention consists of the improvements hereinafter described and finally claimed.

The nature, characteristic features and scope of the invention will be more fully understood from the following description taken in connection with the accompanying drawings forming part hereof and in which:

Figure 1 is a view in central section of an instrument embodying features of the invention.

Fig. 2 is a front view of the upper portion thereof with the cap in open position and the valve removed therefrom.

Fig. 3 is a top or plan view of the valve.

Fig. 4 is an elevational view thereof; and Fig. 5 is a sectional view thereof.

For the purpose of illustrating my invention, I have shown in the accompanying drawings one form thereof which is at present preferred by me since the same has been found in practice to give satisfactory and reliable results, although it is to be understood that the various instrumentalities of which my invention consists can be variously arranged and organized and that my invention is not limited to the precise arrangement and organization of the instrumentalities as herein shown and described.

In the drawings, the sounding instrument is shown as embracing a tubular casing, the base 11 of which is closed, is cylindrical in form and is of heavy construction, which base terminates in a tapered body 12 of lighter construction. The tapered body is provided with a resilient guide piece 13 for co-operating with the inner wall of a guard-tube when said casing is inserted therein for sounding purposes. Preferably formed integral with the body 12 at the top thereof is an enlarged annular head 14 provided with two sets of laterally disposed lugs 15-16 and with an annular recess 17 located in the top of said head. Pivoted between the lugs 15 is a bolt 18 provided with a butterfly-nut 19 for the purpose of securing to place a cap about to be described. This cap comprises a disk-like member 20 hinged between the lugs 16 of the head 14 and provided with spaced laterally disposed lugs 21 adapted to assume an lining relation with the lugs 15 when the cap is in closed position. Communicating with the atmospheric air at a point between the lugs 21 and extended horizontally through the cap is a channel 22 which extends as far as and in turn communicates with a central, vertically disposed, downwardly extended channel 23. This channel 23 extends down through the disk-like member 20 and through a nipple 24 preferably formed integral therewith. Surrounding the nipple 24 is an annular recess 25 adapted to register with the annular recess 17 when said cap is in closed position. Removably seated upon the under face of member 20 is a one piece valve of non-returnable characteristics constructed of pliable material as rubber. This valve embraces a generally disk-like

2

member recessed upon its upper face as at 26 and provided upon its opposite face with a depending rectangular extension 27 having a slit-like passage entirely therethrough. 5 This passage extends vertically therethrough and communicates with the apertured portion 28 of the disk-like member. This aperture in turn fits over the nipple 24 of the cap, recessed portion 26 abuts against the 10 part 29 of the cap and the annular and rounded rim of the valve seats within the annular recess of the cap. The walls of that portion of the extension 27 located adjacent the bottom of the valve are thinner 15 than are the lower walls thereof. By such construction, the thickened walls of the extension abut and the thinner walls are spaced so that the walls of the portion of the aforesaid passage in communication 20 with aperture 28 of the valve are appreciably separated at all times and the walls of the passage at the bottom of said extension are closed except when water under pressure forces them apart in passing to 25 the casing 10. That portion of the extension 27 wherein the thin walls connect with the under face of the valve may be reinforced as at 29' to provide strength and stability. With the cap including the valve 30 which adheres thereto moved into operative position upon the casing head, the rounded under portion of rim 30 of the valve is seated within the annular recess of the head and as the cap and head are clamped together by the bolt and nut connection before mentioned, the lower and upper rim portions of the valve coöperate with the recesses in the head and cap to provide an efficient gasket or washer to prevent leakage. 35

40 The rim 30 is circular in cross-section, see Fig. 5.

The above described instrument is used in the well understood manner of obtaining soundings and in operation water passes between the lugs of the head and cap and finds its way by channels 22-23 and aperture 28 to the passage through the extension 27 of the valve at which point pressure of water causes the lower walls of the extension 45 to separate sufficiently to form an intake orifice to permit water to pass within the casing 10. It is essential in an instrument for making soundings depending upon atmospheric pressure for its operation that air contained in the casing 10 shall not escape to the atmospheric air during a sounding period. It is necessary that the air contained in the casing 10 shall be confined and compressed by the pressure of water, which 50 compressed by the pressure of water, which 55 of course increases with the depth of water being sounded and that the difference in pressure between the air compressed and the weight of water determines the amount of

water admitted to the casing 10. In this respect the valve above described being of 65 non-returnable characteristics precludes the possibility of air within the casing 10 finding its way to the atmospheric air. Likewise during a raising period, it will be understood that the valve acts against return 70 of water in that the walls of the lower end of extension 27 are in abutting relation thus preventing escape of water as well as air. This is important since an accurate test may be made in that no water has escaped from 75 the casing 10 during lifting of the instrument. The depth of water within the instrument for taking soundings may be measured with a suitable scale, as is well known, in order to ascertain the depth to which the 80 instrument has been lowered.

It will now be apparent that I have devised a novel and useful construction which embodies the features of advantage enumerated as desirable in the statement of the invention and the above description and while I have in the present instance shown and described the preferred embodiment thereof of which has been found in practice to give satisfactory and reliable results, it is to be 85 understood that the same is susceptible of modifications in various particulars without departing from the spirit or scope of the invention or sacrificing any of its advantages. 90

95 What I claim is:

In combination, a casing having a closed bottom and an open top which top has an annular recess therein, a cover hinged to said casing, which casing is provided with a nipple surrounding which is an annular 100 recess, there being a channel in communication with atmospheric air extending through said nipple, a thin, flat member of pliable material having a depression therein surrounded by a rim of circular cross-section 105 fitted between said casing and cover, the rim of said member being accommodated by said recesses and said nipple fitting within said depression, which member has projected from the central part thereof an extension 110 having a slotted portion extended therethrough in register with the channel in said cover, the upper part of which slit is open and the lower part of which is normally closed in a yielding position, there being appreciable clearance between the said rim and said extension to permit the extension to 115 freely enter said casing during the closing of the cover and means for clamping said cover to place.

120 In testimony whereof, I have hereunto signed my name.

JOHN L. H. HAND.
